UNITED STATES PATENT OFFICE.

WILLIAM RADLEY, OF SANDWICH, ILLINOIS.

COTTON-SEED PLANTER.

SPECIFICATION forming part of Letters Patent No. 392,689, dated November 13, 1888.

Application filed January 20, 1887. Renewed March 30, 1888. Serial No. 269,006. (No model.)

To all whom it may concern:

Be it known that I, WILLIAM RADLEY, of Sandwich, in the county of De Kalb and State of Illinois, have invented certain new and useful Improvements in Cotton-Seed Planters, of which the following is a description, reference being had to the accompanying drawings, in which—

Figure 1 is a side elevation of my improved planter. Fig. 2 is a detached view of the agitator-shaft, showing the means whereby the agitator-arms are secured thereto. Fig. 3 is a view of one of the agitator-arms. Fig. 4 is a side elevation of the feeding mechanism. Fig. 5 is a top view thereof. Fig. 6 is a top view thereof with the case F removed. Fig. 7 is a transverse section on the line 7 7 in Fig. 6. Fig. 8 is a transverse section of the shaft N, near one of the agitators P.

My invention relates to the feeding mechanism especially adapted to cotton-seed planters, but also adapted to planters for feeding other kinds of seed and to fertilizer-distributors.

The object is to provide novel force-feed mechanism which may be quickly and easily adapted to feed the seed in any desired quantity.

To this end it consists in the construction and combination of parts herein fully shown and described, and pointed out definitely in the claims.

The invention in its preferable form is illustrated in the drawings, wherein A represents the side bars of the planter-frame, to which the axle b of the ground-wheel B is journaled. C represents the hopper secured to said frame in any appropriate manner.

Journalized, preferably, to the extensions h h of the plate H, which, as shown, forms the bottom of the hopper, is the shaft D. The arms E are rigidly secured to the shaft D in any appropriate manner. A cam, I, is loosely mounted on the shaft D, and means are provided for holding this cam at any point in its revolution upon said shaft. The means shown consist of a toothed wheel, i, which is preferably made integral with said cam and so arranged that the bore through which the shaft D passes is central with said wheel, and a latch, h', which is pivoted to an upward ex-

tension, h', of the plate H and adapted to engage between the teeth of said wheel.

F represents a case or cover, preferably of sheet metal, which is loosely mounted on the cam I in any suitable manner—as, for example, by means of the collar f, which loosely surrounds the cam and is fastened to the case F. The case is provided with slots f' in the rim, through which the arms E project, and it is made, preferably, in two parts, like a box and its cover, so that it may be placed in the position shown about the arms E, with their ends protruding, after which the two parts of the case may be secured together. The slots f' should be somewhat longer than the thickness of the arms E, in order that, since the arms are rigidly fixed, the case may be adapted to occupy all the positions in which it will be placed by the revolution of the cam.

The case and the arms E project through a slot in the rear of the hopper, and so much of the arms E as project through the slotted rim of the case into the hopper are in contact with the seed and are operative to force it through the slot c' in the bottom of the hopper into the conductor-tube M.

Surrounding the cam I is preferably a yoke, K, having an arm, k, which is secured to the throat-plate L. This throat-plate is adapted to slide back and forth on the plate H, and is caused to so slide by the backward and forward movement of the arm k. The throat-plate L is provided with a slot, l, into which the edge of the case passes, and the slot is narrowed at the point through which the arms E pass to the proper width for the passage of the seed.

Upon the outer end of the shaft D a sprocket-wheel, d, is secured, which is connected by a drive-chain to the sprocket-wheel b' on the shaft b of the ground-wheel. The revolution of the ground-wheel causes, through the above-named instrumentalities, a revolution of the shaft D. As the shaft revolves, the arms E revolve and engage with the seed and force it through the slots l and c' into the conductor, from whence it drops into the furrow made by the hoe. As the arms E revolve, they, by pressing against the ends of the slots f', carry the case with them; but as the case revolves about a different center from that about which

the arms E revolve—to wit, the center of the cam—the arms E will not all project equally from the case. When the cam lies upon one side of the shaft, the arms E will project farthest on the opposite side; but, as the cam is held in a fixed position when the arms are revolving, all of the arms will project equally at any given point in their revolution. If it is desired to feed rapidly, the arms E are made to project the farthest at or near the point where they pass through the slot l, in which case the center of the cam I lies on the opposite side of the shaft D, and the case F is drawn in that direction. The cam is held in this position by the engagement of the latching-arm h² with the toothed wheel i. When it is desired to reduce the feeding capacity of the arms E, the cam is released from its latching-arm h² and revolved about the shaft D to the desired position, where it is held by the latch. This brings the case F forward and, in revolving about its center in the new position, makes those parts of the arms E that are available at the feeding-point shorter than before, but of equal length. At the same time the cam moves the yoke K, which slides the throat-plate L backward, always holding it in the same position relative to the case F. The width of the slot l is therefore always constant, while the length is varied simultaneously and equally with the variation in the length of the operative parts of the feeding-arms E as the case F approaches and recedes from the end of the slot c'.
 35 With the above-described construction the case can quickly be placed so that no seed at all will be fed by moving the cam so that the arms within the hopper are almost wholly within the case, and it is designed to so place the parts when going to or returning from the field. It is believed that this is a much simpler way to prevent the waste of seed than to be obliged to disconnect some of the parts to prevent the operation of the feeding mechanism. In many respects the precise form shown can be varied without departing from the spirit of the invention. For example, the shaft D may be supported in bearings on one side only of the feeding-arms, and said arms may be secured to its free end, while the case F, while inclosing said arms, may be mounted on the free end of another shaft, the position of which may be made adjustable in any appropriate manner. This construction would contain the essential principle of this part of the invention, as described and claimed—that is to say, it would contain the arms rigidly fixed to a revolving shaft and a case in part inclosing them and revolving about a different center and means for changing the relative position of said centers. The shaft D may be driven, through gear-connection, by the ground-wheel shaft, or in any suitable manner. The form of the locking mechanism may be changed to any form of set-screws or pins; but I believe the simplicity and ease of adjustment of the

form shown makes it preferable to any other. The throat-plate L and its connection with the cam I might be dispensed with; but that would render the slot in the bottom of the hopper too wide for most uses. I consider the throat-plate and its simultaneous adjustment with the case F for some purposes a necessary feature and for all purposes a valuable one. In like manner various parts of the invention may be replaced by other elements to perform the same or similar functions in connection with the remaining parts of the above-described invention. 70

In the planting of most seed it is desirable, and in planting cotton-seed well nigh indispensable, that revolving agitators or stirrers be located in the hopper to insure that the seed shall not get piled up out of reach of the feeding-arms. For this purpose I provide the shaft N, operating within the hopper and mounted in suitable bearings thereon, and to this shaft the agitators P are secured. This shaft N may be revolved by the chain R, which engages with the sprocket-wheel n on said shaft, or in any other suitable manner, and the agitators may be of any suitable form and be secured to the shaft by any appropriate means. For simplicity of construction, however, and because of the ease with which the agitators may be secured to the shaft originally or replaced when broken, I prefer the novel construction illustrated in Figs. 2 and 3 of the drawings. In these figures, N represents the shaft, P the agitators, and S a collar which is adapted to be slipped over said shaft. The agitators consist of three integral parts—viz., the central portion, p, which is substantially semicircular in form and is adapted to fit close around the shaft N, and the arms p' on each side thereof. 90

The collar S is provided with interior annular grooves, s, as many in number as there are agitators P. A slot or slots, s', preferably a spiral slot formed by removing one-half of the wall of the collar to within a short distance from both ends, (or, more properly, by casting the collar with the wall so removed,) is formed in the collar. The agitators are inserted through this slot with the bent part p resting in the annular groove s, while the arms p' extend on each side at right angles to the collar. The shaft N is passed through the collar and the agitators are keyed in place thereby, as shown. To prevent them from revolving about the shaft the collar S is fastened to the shaft by the set-screw s² or by any other appropriate means. It is obvious that the same effect would be produced, though less economically, if, instead of one spiral slot, a series of independent slots were made in the collar, which would permit the agitator-bars to be inserted and lie with their bent portion partly surrounding the shaft N. 110

Having thus described my invention, what I claim as new, and desire to secure by Letters Patent, is—

1. The combination of a shaft having arms

- rigidly secured thereto and a case which in part incloses said arms, having slots in the rim through which the said arms project, and means for revolving said case about a different center from that about which the arms revolve, with means for placing and holding the center about which the case revolves in any desired position, for the purpose set forth. 5
2. The combination of a shaft and feeding-
10 arms rigidly secured thereto with a case partially inclosing said arms, and having an adjustable center about which it revolves.
3. The combination of a shaft and feeding-
15 arms rigidly secured thereto with a case which partially incloses said arms and is caused to revolve by engaging with said arms.
4. The combination of a shaft and feeding-
20 arms rigidly secured thereto with a case partially inclosing said arms and revolving about a different center from that of the arms, and means for changing the relative position of said centers, for the purpose specified.
5. The combination of a shaft and arms rigidly secured thereto with a cam loosely
25 mounted on said shaft, a slotted case mounted on said cam and in part inclosing said arms, and locking mechanism for holding said cam in any desired position, for the purpose specified.
6. The combination of a shaft and arms rigidly secured thereto with a cam loosely mounted on said shaft, a sliding throat-plate, a yoke-arm connecting said cam and throat-
30 plate, and locking mechanism for holding said cam in any desired position, for the purpose set forth.
7. The combination of a shaft and arms secured thereto with a cam loosely mounted on said shaft, having a toothed wheel at one end, a slotted case mounted on the cam and inclos-
35 ing in part the said arms, and a latch adapted to engage with said toothed wheel, substantially as and for the purpose set forth.
8. The combination of a shaft with a cam loosely mounted on said shaft, a toothed wheel secured to said cam, and a latch adapted to engage with said toothed wheel, for the purpose specified. .
45
9. In a cotton-seed planter, a cam having integral therewith a toothed wheel and hav-
ing a bore which passes through both cam and wheel, but central with said wheel. 50
10. In a cotton-seed planter, a shaft and arms rigidly secured thereto, combined with a slotted hopper, through the slot of which said arms operate to feed the seed, and means for increasing and diminishing at will the operative length of the feeding-arms, for the purpose specified. 55
11. The combination of a shaft and a collar having one or more slots through the walls thereof with an arm or arms adapted to pass through said slots and lie with a bent central part between the collar and shaft, and with the ends projecting through said slots, and means for securing the collar to the shaft, substantially as and for the purpose specified. 60
12. The combination of a collar having one or more interior transverse grooves which extend partly around said collar, and having the wall of said collar cut away transversely opposite to each groove, with an arm or arms having a bent central part adapted to rest in said grooves, a shaft which passes through said collar, and means for securing the collar to the shaft, substantially as and for the purpose specified. 70
13. The combination of a revolving shaft, arms rigidly secured thereto, with a two-part case having a slotted rim, said arms and case adapted to revolve about different centers, and means for changing the position of the center about which the case revolves, substantially as and for the purpose set forth. 75
14. The combination of a shaft and a slotted collar with agitator-arms having a bent central part adapted to lie within the collar and around the shaft, and means for securing the collar to the shaft, substantially as specified, and for the purpose set forth. 85
15. A collar having about one-half of the walls removed spirally to within a short distance of the ends and having internal annular grooves, substantially as and for the purpose specified. 90
